UNITED STATES PATENT OFFICE.

THOMAS A. BRAGG, OF TOLEDO, OHIO, ASSIGNOR TO THE OWENS BOTTLE COMPANY, OF TOLEDO, OHIO, A CORPORATION OF OHIO.

SPEED-REGULATING MEANS.

1,358,929.

Specification of Letters Patent. Patented Nov. 16, 1920.

Application filed June 11, 1919. Serial No. 303,395.

To all whom it may concern:

Be it known that I, THOMAS A. BRAGG, a citizen of the United States, residing at Toledo, in the county of Lucas and State of 5 Ohio, have invented new and useful Improvements in Speed-Regulating Means, of which the following is a specification.

My invention relates to an improvement in machines for engraving or sinking dies, 10 or reproducing in cameo or intaglio, and particularly to the type of machine disclosed in the patent to Keller and Warman, No. 956,769, May 3, 1910.

In said patent there is described a machine especially adapted to reproduce dies of the same size and contour as the templet or model. An object of the present invention is to provide means to materially increase the output of a machine of this character.

In the accompanying drawings:

Figure 1 is a front elevation of a machine embodying the principles of my invention.

Fig. 2 is a sectional view at the line 2—2, Figs. 1 and 6.

Fig. 3 is a side elevation of the machine.

Fig. 4 is a rear view of a portion of the machine showing electrical connections.

Fig. 5 is a detail view of the finished work.

Fig. 6 is an outline view of a machine driven by a continuous motor, a reversing clutch being employed.

Fig. 7 is a detail showing the adjustable cams for actuating a switch controlling the speed of the motor.

Fig. 8 is a sectional view of the multiple speed reversing clutch.

Fig. 9 shows a hand lever for shifting speeds.

Fig. 10 is a diagram showing a modification of the electrical speed controlling apparatus.

Referring to the drawings, the machine is mounted on a base 8 from which rises a standard 9, on the upper end of which is supported a horizontally disposed frame 10. Mounted to travel horizontally on the frame 10 is a plate 11 having vertical arms 12, 45 13 projecting therefrom, which through pivotal connections 14, 15 carry a frame 16. Through the above construction the frame 16 is caused to travel horizontally with the plate 11 and at the same time is permitted 50 to swing about its pivot connections.

Mounted on this swinging frame and central to its axis of oscillation is a motor 17 provided with a pulley 18, around which passes a belt or rope 19 to pulleys 20, for driving the cutters. Mounted on the forward end of the frame 16 are cutters 21 and a tracing tool 22, the latter located in a vertical line with the cutters and equidistant from the line of the pivots 14, 15. The cutters and tracing tool are movable horizontally with the swinging frame toward and from the work 23 and templet 24.

Attached to the plate 11 is a bar 25 (Fig. 3) which carries a roller 26 supporting a cable 27 attached at one end to the frame 16 at a point 28, and having a weight 31 attached to its other end, for holding the cutters in contact with the work. For reciprocating the slide 11 carrying the frame 16 and the cutters, any approved mechanism 75 may be used, as for example, that disclosed in the patent to Keller and Warman heretofore mentioned.

A vertically disposed face plate 32 carrying the work and templet is mounted to reciprocate vertically on the vertical frame 33 on the standard 9. On the rear of the face plate is an extension 34 (Fig. 2) having screw threads formed therein, in which runs a screw 35. Mounted on the base 8 is a motor 36, having attached to its shaft 37 a gear 38, meshing with a gear 39 attached to a shaft 41, said shaft connected to the screw 35 by the coupling 30. From this construction it will be seen that when the screw is 90 rotated, the face plate will be moved vertically either upwardly or downwardly, according to the direction of rotation of the motor.

Attached to the face plate 32 is an extension 42 through an opening in which passes a rod 43, connected at its lower end to a reversing switch 46 controlling the motor 36. When the screw 35 is rotated in a direction to move the plate 32 upwardly, the extension 42 engages a stop 44 on the rod 43 and lifts the rod from the Fig. 1 position, thereby throwing the switch 46 and reversing the direction of the motor 36. The face plate then moves downwardly until the stop 42 105 engages a stop 45 on the rod 43 and throws the switch to the Fig. 1 position, again reversing the direction of the motor. Thus a continuous reciprocating of the plate 32 is obtained. The reversing switch 46 is held 110

in its respective positions by a spring actuated stop 47.

Mounted in an extension 50 of the main standard 9 is a column 51 having one end 5 formed in a yoke 52, pivotally supporting a cross arm 53 at a fulcrum 54. Attached to the cross arm at a point 55 is a chain 56 carrying a counter-weight 57, which acts to counter balance the face plate 32. On the 10 opposite end of the cross arm is a segment 60 to which a chain 61 is attached at 62, whereby the pull of the chain is always vertical or in the direction of the axis of the screw 35. With the above described 15 construction it will be seen that any unnecessary strain on the motor will be eliminated.

Referring to Fig. 5, in which is shown a sectional view of the work 23, it will be 20 noted that between the points 63, 64 there is a surface 65 which is substantially straight or free from any sharp curves or abrupt changes in direction and thereby permits the cutting tool to make a substantially straight cut of considerable length. In making this straight cut a comparatively high speed is permissible, whereas, in cutting along the surfaces 66 and 67 where the direction of movement changes abruptly or 25 is irregular, the movement must be comparatively slow to permit the tracing tool accurately to follow the pattern. Heretofore it has been customary to maintain throughout the cutting a uniform speed, 30 slow enough to permit accurate cutting where the pattern is irregular in outline. The present invention provides means to speed up the work while the cut is being made along a straight surface or a portion 35 devoid of any abrupt changes in direction; and thereby greatly increase the output of the machine. For this purpose, the speed 40 of the motor 36 is automatically varied and controlled, as will presently appear.

Referring to Fig. 4, a circuit for the field winding of the motor 36 may be traced from the positive main A, through conductor A', resistance coil 68, rheostat 69, field coils of motor 36 and a return conductor B' to the 50 negative main B. The resistance 68 permits the motor to run at a comparatively high speed adapted for the straight cut along the surface 65, while the rheostat allows for manual regulation of the speed. 55 For cutting out the resistance 68 and reducing the speed of the motor, a shunt circuit is provided around the resistance, comprising a conductor A² and switch 70.

Attached to the face plate 32 (Fig. 4) 60 is a rod 71 on which are mounted cams 81 and 82 individually adjustable up and down on the rod. Mounted on the frame 33 is a switch box 70 carrying a switch controlled by the cam. The switch comprises a switch lever 72 pivoted at 73 and carries a roller

74 at one end and a contact 75 at the other end. Also mounted in the switch box is a stationary contact 76 connected to the rheostat through line A².

Assuming that the face plate 32, which 70 has a vertical reciprocating movement, is on its downward stroke and the cutter making its straight cut, the contacts 75, 76 are held apart by a spring 84 so that the resistance 68 is in the motor field circuit. 75 The motor 36, therefore, runs at a high speed while the cutter is on the straight surface 65. As the switch roller engages the cam 81, the switch is closed, thereby short circuiting the resistance 68, so that 80 the motor is slowed down to a speed suitable for cutting along the irregular surface 67. This reduced speed is maintained until the face plate has completed its down stroke. The motor is then reversed and 85 runs at reduced speed until the face plate has traveled upward far enough to release the roller 74 from the cam 81 and permits the switch to open, thereby speeding up the motor. The motor maintains its increased 90 speed until the roller engages the cam 82, again closing the switch and slowing down the motor for the cut along the surface 66.

From the above description it will be 95 seen that the speed of the face plate 32 is greater in the middle of its stroke than it is on the ends of its stroke, thereby allowing for a slow cut on the sharply curved or irregular surfaces and a fast cut on the straighter surface, thus materially increasing 100 the speed of production. By adjusting the cams 81 and 82 up or down, the points at which the speed changes can be adjusted to suit the work. The rheostat 69 serves in the usual manner as a means to manually 105 regulate the speed of the motor.

Fig. 6 shows an arrangement in which a combined reversing clutch and speed changing gear device 90 is interposed between the motor 36 and the screw shaft 35. The motor 110 is thus permitted to run continuously in one direction, the reversal of the screw shaft 35 being effected by operating the clutch lever 91 connected to a rod 431 which corresponds in function and operation to the rod 43 115 (Fig. 1).

The combined reversing clutch and speed changing device, as shown in detail in Figs. 8 and 9, is of standard construction and in itself is not a part of my invention. This 120 apparatus comprises a central vertical shaft 94 to which is secured a worm wheel 95 running in mesh with a worm 96 on the motor shaft 37. A clutch sleeve 98 splined on the shaft 94 is shiftable up and down by means 125 of the clutch lever 91. The clutch sleeve 98, as shown in Fig. 8, is in an intermediate position, so that the shaft 94 runs idly. When shifted downward by lowering the lever 91 the clutch sleeve engages a clutch 130

plate on a bevel gear 99 loose on the shaft 94 and connected through an idler gear 100 to drive a gear 101. The gear 99 being thus connected through the clutch sleeve to the shaft 94, is driven by the latter in the same direction in which the shaft rotates and through the gear 100 rotates the gear 101 in the reverse direction. The gear 101 has a driving connection with the shaft 35. By shifting the clutch lever up the clutch sleeve is disconnected from the gear 99 and connected directly with the gear 101, thereby driving the shaft 35 in the same direction as the shaft 94.

15 A direct driving connection between the worm wheel 95 and the shaft 94 is effected by a dog 200 pivoted within the hollow shaft 94. For driving at higher speeds, speed multiplying gearing is provided, which comprises 20 a gear 102 keyed to the hub of the worm wheel 95, gears 103, 104 and 105 mounted on the shaft 94 to rotate independently thereof, and pinions 106, 107, 108 and 109 meshing respectively with the gears 105, 104, 103 and 25 102, said pinions being keyed to rotate with a sleeve 110 on which they are mounted. The dog 200 is shiftable vertically downward to connect with any one of the gears 103, 104 and 105. For this purpose said dog 30 is mounted on a rod 111 slidable in the hollow shaft 94, said rod having rack teeth to engage a pinion 112 on a horizontal shaft 113 provided at its outer end with a pinion 114 to mesh with a gear segment 115 on a 35 stud shaft 116 to which is attached a hand lever 117. The latter is provided with a latch 118 to hold it at any one of the four positions in which the dog 200 connects with the respective gears. By shifting the dog 40 200 downward into engagement with the gear 103 the motion is transmitted from the worm wheel 95 through gears 102, 109, 108 and 103, thereby decreasing the speed. In like manner power may be transmitted 45 through gears 107 and 104 to further decrease the speed, also gears 106 and 105 to obtain the lowest speed.

Fig. 10 shows diagrammatically an arrangement in which the resistance 68 of 50 Fig. 4 is omitted, the automatic switch being arranged in a shunt circuit around the rheostat 69. With this arrangement the closing of the switch short circuits the rheostat 69, thereby strengthening the motor field and causing a reduction of speed. This arrangement permits the relative speed of 55 the work during the slow and fast cuts to be adjusted through a wide range by adjusting the rheostat. At the same time the speed 60 of the work relative to that of the motor may be regulated and adjusted by the speed changing gearing controlled by the lever 117.

What I claim is:

65 1. In a machine of the character de-

scribed, the combination with a horizontal reciprocable plate, a horizontal swinging frame thereon, a vertically reciprocating face plate, a pattern and tracer carried by the said frame and face plate, and means to 70 operate said vertically reciprocating plate at an automatically variable speed.

2. The combination of a tracer, a pattern in contact therewith, means for causing the tracer to repeatedly traverse the pattern, 75 and automatic means to cause a comparatively slow relative movement of the tracer and pattern during predetermined portions of each said traverse and a more rapid movement during other portions of the traverse. 80

3. The combination of a tracer, a pattern, a motor for reciprocating one of said parts and thereby cause the tracer to repeatedly traverse the pattern, and automatic means to reduce the speed of the motor and cause a 85 relatively slow movement of the tracer and pattern during a predetermined portion of each traverse and to increase the speed of the motor and thereby increase the speed of said relative movement during another portion of the traverse. 90

4. The combination of a work carrying plate, a templet on said plate, a tracer, a cutter, means to hold the tracer and cutter to the templet and work piece respectively, 95 an electric motor, driving connections between the motor and said plate for reciprocating the latter and causing the tracer to repeatedly traverse the templet and the cutter to traverse the work piece, said templet 100 presenting a comparatively straight path for the tracer during a portion of each reciprocation, and an irregular or direction changing path during another portion of the traverse, and automatic means for causing the motor to run at a comparatively high speed while the tracer moves along said straight path. 105

5. The combination of a work carrying plate, a templet on said plate, a tracer, a 110 cutter, means to hold the tracer and cutter to the templet and work piece respectively, an electric motor, driving connections between the motor and said plate for reciprocating the latter and causing the tracer to 115 repeatedly traverse the templet and the cutter to traverse the work piece, said templet presenting to the tracer a surface substantially parallel to the direction of movement of said plate during a portion of its movement, and an irregular surface during another portion of its movement, and automatic means for accelerating the speed of the motor while the tracer traverses said parallel surface. 120

6. The combination of a work carrying plate, a templet on said plate, a tracer, a cutter, means to hold the tracer and cutter to the templet and work piece respectively, an electric motor, driving connections be- 130

- tween the motor and said plate for reciprocating the latter and causing the tracer to repeatedly traverse the templet and the cutter to traverse the work piece, said templet 5 presenting a comparatively straight path for the tracer during a portion of each reciprocation, and an irregular or direction changing path during another portion of the traverse, automatic means for causing the 10 motor to run at a comparatively high speed while the tracer moves along said straight path, and means to adjust the relative speed of the motor for said straight and irregular portions of the work.
- 15 7. The combination of a work carrying plate, a templet on said plate, a tracer, a cutter, means to hold the tracer and cutter to the templet and work piece respectively, an electric motor, driving connections be- 20 tween the motor and said plate for recipro-

cating the latter and causing the tracer to repeatedly traverse the templet and the cutter to traverse the work piece, said templet presenting to the tracer a surface substantially parallel to the direction of movement 25 of said plate during a portion of its movement, and an irregular surface during another portion of its movement, automatic means for accelerating the speed of the motor while the tracer traverses said parallel 30 surface, manual means to regulate the amount of said acceleration, means to regulate the speed of the work carrying plate relative to that of the motor, and means to adjust the point at which the speed is 25 changed.

Signed at Toledo, in the county of Lucas and State of Ohio, this 9th day of June, 1919.

THOMAS A. BRAGG.
